UNITED STATES PATENT OFFICE.

WILLIAM N. BOX, OF NORTHFIELD, AND HAUGHTON BROWN, OF MINNEAPOLIS, MINNESOTA,
ASSIGNORS TO NELS J. BLOMGREN, OF MINNEAPOLIS, MINNESOTA.

MOLD FOR BUILDING-BLOCKS.

No. 911,110.

Specification of Letters Patent.

Patented Feb. 2, 1909.

Application filed February 9, 1905, Serial No. 244,867. Renewed January 18, 1908. Serial No. 411,498.

To all whom it may concern:

Be it known that we, WILLIAM N. BOX, of Northfield, Brown county, Minnesota, and HAUGHTON BROWN, of Minneapolis, Hennepin county, Minnesota, have invented certain new and useful Improvements in Molds for Building-Blocks, of which the following is a specification.

The object of our invention is to provide a machine in which a concrete building block can be easily and quickly molded.

A further object is to provide a mold particularly adapted for forming a block composed of sections separated by an air space and connected across such space by a non-conducting material such as wood.

A further object is to provide improved means for tilting the side and end walls of the mold outwardly to expose the completed block.

Other objects of the invention will appear from the following detailed description.

The invention consists generally in various constructions and combinations, all as hereinafter described and particularly pointed out in the claims.

In the accompanying drawings forming part of this specification, Figure 1 is a plan view of a building block mold embodying our invention. Fig. 2 is a plan view of the mold looking at the under side. Fig. 3 is a longitudinal vertical section showing the mold closed and ready for use. Fig. 4 is a similar view showing the walls tilted outwardly to allow the convenient removal of a block. Fig. 5 is a transverse vertical section through the mold and the block therein. Fig. 6 is a similar view showing the walls tilted away from the block and illustrating the position of the connecting means between the sections. Fig. 7 is a detail view of the connection between the side and end walls of the mold.

In the drawing, 2 represents a suitable base or frame having legs 3 and centrally arranged bar 4 extending lengthwise of the base, and a strengthening cross-bar or brace 5 connecting the bar 4 near the middle of the machine with the side rails. These rails and bars form a skeleton base or frame to receive a movable floor 6 upon which the block is molded. This floor is divided longitudinally into two sections connected at the ends by straps 7 and provided with end recesses 8 and circular holes 9 near the middle to receive the cores,

as will hereinafter appear. After the block has been molded and the walls tilted outwardly from it, the floor, with the block thereon, is removed from the mold by means of suitable tools. Pivoted upon each side of the bar 4 are vertically arranged plates 10 extending from end to end of the mold and separating one side from the other and provided with semi-circular cores 11 arranged in pairs and adapted to enter the holes 9 in the floor and form the central cores for the block. These plates and cores are preferably made from castings hinged on the frame of the mold as described, and while removable from the mold, if necessary, are intended to be permanently fixed thereon, only to be taken off in case of breakage or preparatory to shipping or packing the mold. The plates are separated from one another a distance equal to the width of the bar 4, as shown in Figs. 5 and 6, and when adjusted preparatory to molding the block will cause the formation of an air space therein extending from the top to the bottom. This manner of mounting the cores in the mold permits their expansion preparatory to filling the mold and their contraction after the block is formed to facilitate its removal. Ordinarily, the cores are removed either at the bottom or top of the mold, but we have found that by arranging the cores in the manner described that much less labor is involved in the formation of the blocks, and particularly where an air space is formed between the inner and outer sections. We therefore regard the expanding and contracting features of our cores as an important part of our invention. A bar 12 is adapted to drop into the space between the upper edges of the plates 10 and hold them apart and prevent the cement and sand from entering the air space, and this bar is preferably provided with a strap 13 on its upper edge that is hinged at 14 to one of the end walls 15, and is provided with a snap or catch 16 to engage the other end wall, and thereby aid in holding the walls in alinement during the operation of molding.

When it is desired to tilt the walls outwardly and remove the block, the bar 12 is swung on its pivot to uncover the air space between the block sections and permit the end walls to be separated. The end walls have brackets 18 at their lower ends pivoted on the base, and are provided with cores 19 centrally arranged on their inner face and

adapted to overhang the recesses in the ends of the floor 6 when the mold is being set up preparatory to use. The plates 10 are also provided on each side of the cores 11 with 5 vertical slots 20, wherein wooden pins or bars 21 are laid extending across the air space and tying the block sections together. The ends of the pins or bars preferably extend out to the surface of the block on each side to form 10 nailing surfaces for furring strips, or interior or exterior finish. These bars or pins are preferably dipped in a preparation of tar before being placed in the mold to prevent them from being affected by the moisture in 15 the green block and swelling or cracking and damaging the block. The end walls preferably project beyond the sides of the machine to adapt the mold for forming blocks of different size and are pivotally connected near 20 their upper ends by rods 22 with blocks 23 that are slideable on rods 24 horizontally arranged in the base of the machine substantially in line with the bar 4. These blocks slide freely back and forth on the rods and 25 permit the quick and convenient adjustment of the end walls. A bar 25 is centrally pivoted on the bar 4 on the under side of the machine, and has its ends connected by rods 26 with the block 23, suitable turn-buckles 30 27 being provided to permit convenient adjustment of the said blocks. An operating lever 28 is mounted on the bar 25 and adapted to be swung back and forth lengthwise of the machine to swing the end walls in and out 35 35 to close or open the mold. The side walls 29 are provided at their lower edges with brackets corresponding to those on the end walls, pivoted on lugs 30 which extend horizontally from the side rails of the machine frame, and 40 have a series of holes 32 to permit the adjustment of the side walls toward or from each other to increase or decrease the width of the block. The ends of these lugs are substantially flush with the projecting ends of 45 the end walls, and curved pins 33 are provided on said side walls to enter holes 34 in the end walls to cause a corresponding movement of the side walls when the end walls are operated. The pins 33 are inserted into the 50 proper hole in the end walls according to the pivotal position of the side walls on their lugs and the width of the block to be formed.

In operation the removable floor is placed on the base and the walls of the mold closed. 55 The bar 12 is then inserted into the space between the upper edges of the plates 10 forcing them apart and causing them to assume a vertical position with an air space between them, and the wooden bars 21 having been 60 previously placed in position the operator fills the mold with the material from which the block is to be formed and tamps it firmly therein. The bar 12 is then lifted and tilted over to one end of the machine, the side and 65 end walls are swung outwardly away from

the block, and the floor and block thereon, in a green state, are lifted and moved away to a suitable place to dry. Another floor is then put into the mold and the operation described repeated.

Whenever desired the position of the side walls on their supporting lugs can be changed to vary the width of the block, and a corresponding floor used to accommodate the difference in the width of the space between the 75 walls.

We claim as our invention:

1. The combination, with a suitable base, of side and end walls hinged thereon, rods supported at one end in the ends of said base 80 and extending horizontally therefrom, blocks slidably mounted on said rods, rods pivotally connecting said blocks with said end walls, and mechanism for moving said blocks.

2. The combination, with a base, of side 85 and end walls hinged thereon, guides mounted on said base, blocks slidably supported on said guides and having a pivotal connection with said end walls, means connecting said side and end walls to operate the former simultaneously with the movement of the latter, and mechanism for operating said blocks.

3. The combination, with a base, of side and end walls hinged thereon, curved rods carried by said side walls and having a sliding 95 connection with said end walls, and mechanism for tilting said end walls.

4. In a building block mold, the combination, with a base and the side and end walls, of core plates hinged on said base and dividing the mold into independent compartments or chambers, a space being provided between said plates to form an air space between the sections of the block and said plates having recesses to receive transverse 100 bridging pins, substantially as described.

5. The combination, in a building block mold, with a base, of side and end walls mounted thereon, core plates mounted on said base and dividing the mold into chambers or compartments, said plates being provided with cores semi-circular in cross section arranged in pairs, and a space being provided between said plates, and said plates having slots or recesses to receive bridging 110 pins or bars transversely arranged in the mold, substantially as described.

6. The combination, in a building block mold, with a frame provided with side and end walls thereon, of core plates hinged on 120 said frame with a space between them and extending lengthwise of the mold from end to end and from top to bottom thereof, said plates having slots to receive transverse bridging pins, and means separating the upper edges of said plates, substantially as described.

7. The combination, in a building block mold, with a frame provided with side and end walls, of core plates arranged on said 130

- frame and dividing the interior of the mold into independent compartments; said plates having a space between them, and a bar hinged to one of said end walls and adapted 5 to close the opening between said plates at the top of the mold, and said bar having a catch to engage the other end wall and thereby hold them in proper alinement, substantially as described.
- 10 8. The combination, in a building block mold, with a frame provided on each side with laterally extending lugs each having a series of holes or perforations, end walls hinged at their lower edges to the ends of 15 said frame and projecting on each side beyond the base to a point opposite the outer perforations in said lugs, and side walls hinged on said lugs and adjustable in the holes therein to increase or decrease the 20 width of the mold, and a removable floor adapted to close the space between said side walls at the bottom of the mold.
9. In a building block mold, the combination, with a base and the side and end walls 25 mounted thereon, of core plates arranged on said base and dividing the mold longitudinally, into independent compartments, a space being provided between said plates, means for closing said space at the top of the 30 mold, and said plates having slots or recesses wherein connecting bars or rods are placed and embedded in the block to tie the sections together, substantially as described.
10. In a building block mold, the combination, with a base, of side walls hinged thereon, curved rods carried by said side walls, end walls also hinged on said base and having holes to receive said curved rods, said rods causing movement of said side walls when 40 said end walls are operated, and mechanism for operating said end walls.
11. The combination, in a building block mold, with a suitable frame or base, of side and end walls hinged thereon, said end walls 45 being provided with centrally arranged cores, a removable floor arranged upon said base and having recesses in its ends, core plates mounted on said base near the middle thereof and dividing the mold into separate 50 compartments, an air space being provided between said plates, and said plates having slots extending from their upper edge toward the bottom to receive transversely arranged bars that bridge the space between said 55 plates, substantially as described.
12. In a building block mold, a core capable of expansion preparatory to filling the mold and forming the block and of contraction to facilitate the removal of the completed block, and means hinged at one end 60 and having a vertical swinging movement on its pivot for expanding the core at the top of the mold.
13. A building block mold having core 65 plates and core sections mounted thereon,
- a space being provided between said plates, and said plates being movable toward or from each other to allow separation of said core sections preparatory to filling the mold and to allow them to be drawn together to 70 facilitate the removal of the completed block, substantially as described.
14. In a building block mold, the combination, with the side and end walls, of a core capable of expansion preparatory to 75 filling the mold and of contraction to facilitate the removal of the completed block, and means at the top of the mold for expanding the core and locking the end walls together, substantially as described. 80
15. In a mold, the combination, with the side and end walls and base, of a core composed of separable sections arranged to be expanded or contracted, and the opposite sections having openings or recesses to receive a bridging means connecting the sections of a block, substantially as described. 85
16. In a mold, the combination, with a base and the side and end walls, of core plates extending lengthwise of said mold and 90 provided at intervals with core sections, the core sections of one plate being opposite substantially to the corresponding sections of the other plate, and said plates being movable toward or from each other to vary 95 the distance between the opposite core sections, substantially as described.
17. The combination, in a mold, with a suitable base and the side and end walls, of core plates, core sections carried thereby, 100 an air space being provided between the plates and sections separating the mold, and said plates having openings or recesses to receive a bridging means connecting the block sections, substantially as described. 105
18. In a building block mold, the combination, with a base and the side and end walls, of cores composed of movable sections and arranged to divide said mold into compartments, an air space being formed between the core sections when the mold is in use, and said core sections having recesses wherein transversely arranged bars may be placed to bridge said air space and unite the sides of the block, substantially as 110 described.
19. In a building block mold, the combination, with a base and the side and end walls, of cores mounted on said base and composed of separable sections that are 120 movable toward or from each other, and a bar provided at the top of said mold for separating said core sections.
20. In a building block mold, the combination with a base and the side and end 125 walls, of core plates movable toward or from each other, and means arranged to be inserted between the edges of said plates from the outside for separating them preparatory to filling the molding. 130

21. In a building block mold, the combination with the base and the side and end walls, of core plates movable on said base and capable of movement toward or from each other to contract or expand the core, and means inserted between and engaging the edges of said plates for separating them preparatory to filling the mold, substantially as described.
22. In a building block mold, the combination with a base and the side and end walls, of core plates capable of movement toward or from each other to contract or expand the core, and bridging means extending transversely with respect to said plates, substantially as described.
23. The combination in a mold with a suitable base and the side and end walls, of core plates movable toward or from each other, an air space being provided between the plates separating the mold sections, and bridging means for said space arranged transversely with respect to said plates, substantially as described.

In witness whereof, we have hereunto set our hands this 4th day of February 1905.

WILLIAM N. BOX.
HAUGHTON BROWN.
